UNITED STATES PATENT OFFICE.

JEREMIAH A. SCRIVEN, OF NEW YORK, N. Y.

DESIGN FOR A BIFURCATED NETHER GARMENT.

SPECIFICATION forming part of Design No. 31,540, dated September 19, 1899.

Application filed May 29, 1899. Serial No. 718,758. Term of patent 14 years.

To all whom it may concern:

Be it known that I, JEREMIAH A. SCRIVEN, a citizen of the United States, residing in the city, county, and State of New York, have 5 invented and produced a new and original Design for Bifurcated Nether Garments, of which the following is a full, clear, and exact description.

The leading feature of my design is a bifurcated nether garment, substantially as shown in the accompanying drawing, the essential feature of the design being the shape of the insert or panel.

In the drawing, A is the bifurcated gar-

ment, having the tubular members B and the 15 panel or insert C in the back thereof, which panel or insert has the upright edges d and the outer substantially straight upright edges e, terminating at the upper end in the curved edges f.

20

What I claim is—

The design for a bifurcated nether garment, substantially as herein shown and described.

JEREMIAH A. SCRIVEN.
